FIG. 5.

UNITED STATES PATENT OFFICE

JOSEPH C. GUSTAVESON, OF NEW YORK, N. Y.

HAT

Application filed May 8, 1929. Serial No. 361,306.

This invention relates to improvements in hats, and has particular reference to men's hats.

An object of the invention is to provide an improved ventilating means for a hat of simple and practical construction wherein a lazy-tongs arrangement is employed to constitute the head-engaging band so that said band may be readily adjusted to properly fit the head of the wearer and thereby allow for an efficient circulation of air when the hat is being worn.

Another object is to mount an adjustable head-engaging band in the crown of a hat by supporting the same upon one or more mounting plates each of which is designed to receive and retain in cooperative relation therewith a portion of said band whereby the same cannot become inadvertently detached from the crown.

The above and other objects will appear more clearly from the following detailed description, when taken in connection with the accompanying drawings, which illustrate preferred embodiments of the inventive idea.

In the drawings—

Figure 1 is a transverse section through a hat constructed in accordance with the invention;

Figure 2 is a bottom plan view thereof; Figure 3 is a section on the line 3—3 of Figure 2;

Figure 4 is a plan view of one of the mounting plates for the head-engaging band;

Figure 5 is an enlarged fragmentary view, partly in section, of the head-engaging band and the adjusting means therefor;

Figure 6 is a section on the line 6—6 of Figure 5;

Figure 7 is an enlarged transverse section through one of the elements constituting the head-engaging band;

Figure 8 is a view similar to Figure 6, showing a slightly different form of the invention; and

Figure 9 is a perspective view of a portion of the head-engaging band showing a protective plate attached thereto.

The invention is illustrated in connection with a man's straw hat, but its application

to other types of hats will be understood from the following description.

In carrying out the invention there is mounted in the interior of the crown 10 of the hat a head-engaging band, generally indicated by the numeral 11. This band is designed to replace the ordinary sweatband of the hat and to afford an adequate circulation of air through the hat by providing the crown thereof with ventilating openings 12. The band 11, which may be made of any suitable material such as celluloid, comprises a plurality of arms 13 and 14 pivotally connected both at their ends and intermediate the same to constitute a lazy-tongs construction which extends entirely around the interior of the crown and which is expansible and contractible so as to vary the size of the band to comfortably fit the head of the wearer. In the embodiment shown in Figure 5, the upper end of each arm 14 is channeled, as indicated at 15 and clearly illustrated in Figure 7, so as to receive and hold one extremity of a flexible, bowed finger 16, the free portion of which is adapted to engage and conform to the contour of the head, the various fingers being spaced apart so as to permit the passage of air between the same when the band is in position within the crown.

To mount the band within the crown of the hat for circumferential adjustment therein, the invention provides a number of mounting plates 17, such as shown in Figure 4, each of which has a plurality of prongs 18 extending therefrom and adapted to be bent and engaged in the crown 10 to secure the plate in position. Said plate is slightly curved to conform to the contour of the crown and is provided longitudinally thereof with a slot 19 to receive a stud 20 which forms the intermediate pivot for two of the arms 13 and 14. At one end of the slot 19 the plate 17 has struck therefrom a resilient locking tongue 21 which yields under pressure of the stud 20 when the band is being mounted in position to permit of insertion of the stud into the slot, but which restores to a position relative to the slot that will prevent detachment of said stud from the plate. With the band thus supported in position, the lazy-tongs may be

adjusted to expand or contract the band and during such movements the studs 20 will slide back and forth in the slots of their respective mounting plates. For the purpose of adjusting the lazy-tongs two of the arms 13 adjacent each other are formed with extensions 21 and 22, the former having a lug 23 pivoted thereto and the latter extension having the lug 24 pivotally and detachably connected thereto. The lugs 23 and 24 are connected by the oppositely screw threaded rod 25 having the nut 26 thereon which is adapted to be turned in order to rotate said rod whereby the extensions 21 and 22 are adjusted toward and away from each other to contract or expand the lazy-tongs throughout the entire circumference of the band.

In the form of the invention illustrated in Figure 8, the arms 14 of the lazy-tongs, instead of being channeled as above described, have the bowed fingers 16 formed integrally therewith. Otherwise the construction of the band of this embodiment is the same as described in connection with Figure 5.

If desired, the fingers 16 which engage across the forehead may have secured thereto a thin perforated protective plate 27 (Figure 9) which so engages the forehead as to prevent the formation of temporary impressions of the fingers 16 in the skin when the hat is being worn. The plate 27 is bent upon itself along its lower edge, as indicated at 28, and is provided in its upper edge with a plurality of spaced lugs 29 which snap into small notches 30 formed in the edges of the fingers 16 so as to hold the plate in position on said fingers.

A band or trimming 31 may be secured in the crown of the hat adjacent the rim and covers the lower portion of the lazy-tongs construction, as best shown in Figures 5 and 6.

What is claimed is:

1. In a hat, a crown, a head-engaging band in said crown including a lazy-tongs, and a plurality of bowed fingers forming extensions of certain of the arms of said lazy-tongs and having their free ends adapted for engagement with the head of the wearer.

2. In a hat, a crown, a head-engaging band in said crown comprising a lazy-tongs, certain arms of which are channeled, and flexible fingers each having one end mounted in the channel of one of said arms and its free end adapted for engagement with the head of the wearer.

3. In a hat, a crown, a head-engaging band in said crown including a lazy-tongs, adjacent arms of which are formed with extensions, an oppositely screw threaded rod connecting said extensions, means to turn said rod to adjust said extensions in opposite directions to vary the size of said band, and a plurality of bowed fingers carried by said lazy-tongs for engagement with the head of the wearer.

4. In a hat, a crown, an expansible head-engaging band therein, a mounting plate for said band secured to said crown and having a slot therein to receive a portion of said band to guide the same, and a resilient locking tongue formed at one end of said slot and capable of movement relative to said plate to permit the insertion of said portion into said slot, said tongue having a normal position to prevent detachment of said portion from said plate.

In testimony whereof I have affixed my signature.

JOSEPH C. GUSTAVESON.
